DESIGN FOR A COMBINATION HANDBAG AND MIRROR CONTAINER

Samuel R. Goldsmith, New York, N. Y.

Application February 25, 1941, Serial No. 99,202

Term of patent 3½ years

To all whom it may concern:

Be it known that I, Samuel R. Goldsmith, a citizen of the United States and resident of New York city, in the county and State of New York, have invented a new, original, and ornamental Design for a Combination Handbag and Mirror Container, of which the following is a specification, reference being had to the accompanying drawing, forming a part thereof, and of which Figure 1 is a perspective view of a combination handbag and mirror container with the mirror container closed, showing my new design, Fig. 2 is a perspective view thereof with the mirror container open, and Fig. 3 is a sectional view thereof on the line 3—3 of Fig. 2.

The rear of Fig. 1 is substantially plain.

I claim:

The ornamental design for a combination handbag and mirror container, substantially as shown and described.

SAMUEL R. GOLDSMITH.
